UNITED STATES PATENT OFFICE

2,319,471

RAILWAY CAR STRUCTURE

Karl F. Nystrom, Milwaukee, Wis.

Application December 24, 1940, Serial No. 371,529

4 Claims. (Cl. 105—369)

My invention relates to means to anchor the lading directly to the side wall framing of the car to prevent the lading from shifting, which means is desirable for machinery or when only a partial load is in the car. Such means also provides means to support beams extending crosswise of the car for an upper deck (spaced above the floor of the car) for a second tier of lading. Such upper decks are desirable to support the upper part of the lading independently of the lower part of the lading to prevent the upper part from crushing the lower part, such, for instance, as oranges or potatoes and the like when shipped in bulk or light package stuff, such as breakfast foods. Automobile bodies are frequently transported in double deck arrangement. Unfinished tractors may be loaded on the floor of the car and the loose parts thereof placed on the upper deck. These tractors are completed (or assembled as it is called) near point of sale.

Another object is to provide such an anchor and deck supporting means which is so formed that water, grain, sand and other foreign matter which enters the boxlike structure of my device cannot enter the space between the lining and sheathing of the car wall. Such material might cause rot, breed germs or cause an undesirable odor.

In the drawings:

Figs. 1, 2 and 3 show a cross section of a typical railway car showing my improved anchorage and deck beam in the side wall thereof.

Fig. 2 shows the anchorage in the side wall and the deck beam mounted therein.

Fig. 4 is a section on line 4—4 of Fig. 2.

Fig. 5 is a section on line 5—5 of Fig. 4.

Fig. 6 shows the boxlike structure assembled ready for attachment to the posts of the car.

Fig. 7 shows one end of the deck beam.

Fig. 8 shows one of the angular brackets.

Fig. 9 shows one of the U shaped members.

Fig. 10 shows one of the facing members.

Figs. 11—15 inclusive show a modified construction wherein

Fig. 11 shows a horizontal section through the middle of the boxlike structure and an end of the deck beam.

Fig. 12 is a section on line 12—12 of Fig. 11.

Fig. 13 shows a vertical section through the middle of the boxlike structure and an end of the deck beam.

Fig. 14 is a section on line 14—14 of Fig. 13.

Fig. 15 is a section on line 15—15 of Fig. 11.

The drawings show my improved means for anchoring the lading and supporting a deck

beam for double deck loading. Each unit comprises a boxlike structure 1 as shown in Fig. 2, extending between and secured to two vertical side wall posts 2. Several units are positioned on opposite sides of the car and on the same level to support a deck at substantially that level, and other groups of units may be used to support decks at different levels.

Each boxlike structure 1 is made of a pair of spaced brackets or members 4 (see Fig. 6) extending horizontally between and secured to the adjacent vertical posts 2. Each bracket 4 comprises a horizontal flange 6 and a flange 8 at right angle thereto for attachment to the vertical posts 2, with the horizontal flanges 6 extending between the right angle flanges to the outer surface 10 of the lining 12. The U-shaped member 14 (see Fig. 9) extends between the horizontal flanges 6 of the brackets 4 and is welded thereto to form a solid five-sided boxlike structure having the sixth side open to the interior of the car through an aperture in the lining. The solid box prevents foreign matter which enters the box through the aperture from getting between the sheathing 16 and the lining 12 of the car. The arms 18 of the U-shaped member 14 also extend to the inner surface 10 of the lining 12. The facing member 20 (see Fig. 10) extends entirely around the boxlike structure to reinforce it and to provide a backing for the wooden lining 12. The facing member 20 is formed with horizontal flanges 22 which are welded to the brackets 4 for mutual reinforcement. The lining 12 is cut away to provide an aperture for access to the interior of the boxlike structure. A vertical rod or flat bar 24 is positioned within the box structure, which extends between and is secured to the horizontal flanges 6 of the brackets 4 to provide an anchorage for a steel tape, chain or rope or any other convenient means for holding the lading in place. The bar is positioned to provide an opening 25 on each side thereof. The several parts of the boxlike structure are welded together as a unit and then several of these units are preferably welded to the vertical posts before the posts are assembled in the car structure.

A plurality of beams 26 are provided extending crosswise of the car to support an upper deck above the floor of the car. As illustrated, each end of each beam is provided with a pair of T handed extensions or prongs 28 rigidly secured thereto, for instance by welded material as shown at 27 which, when the beam is in use, project into the openings 25 of the boxlike structure

on opposite sides of the vertical post 24 and are retained therein by the little projections 29 which are secured to the lower bracket 4. The beam 26 itself may be of any desired structure. The distance between the ends of the beams 26 and the adjacent T hands 28 is such the T hands at one end of the beam may be projected far enough in the unit in one wall so that the T hands at the opposite end of the beam may be moved opposite the unit in the opposite car wall and then the beam moved horizontally until the T hands at both ends of the beam engage the units in the opposite car walls.

A beam with the same function and of similar structure as the beam 26 shown herein is disclosed and claimed in my co-pending application for Patent No. 350,487 filed August 3, 1940 and a division thereof No. 371,530, filed December 24, 1940.

Figs. 11-15 inclusive show a boxlike structure 40, comprising a piece of pipe 42 closed by the cap 44 at one end only, which pipe is inserted through a bracket 45 and secured by welding or by crimping as shown at 46. The bar 48 is secured to the pipe 40 adjacent the open end thereof. The ends of the bracket 45 are secured to adjacent post or some other part of the wall structure with the open end of the pipe toward the interior of the car for the reception of the deck beam 50.

The end of the deck beams 50 in the modification comprises a tube 52 with a slot 54 in each end thereof which straddles the bars 48 in the boxlike structures in the opposite side walls. One side of each slot is provided with a lip 56 which prevents the easy removal of the deck beams 50 from the boxlike structures.

The central portion of the deck beam 50 is preferably of rectangular cross sections as shown in Fig. 12 and is preferably provided with a wooden insert 58.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a railway car having a wall comprising posts, a sheathing and a lining in combination with an anchorage device supported by said posts and positioned between the sheathing and the lining, said device comprising a five-sided solid box structure having the sixth side open to the interior of the car through an aperture in the lining, a rod within said box structure and accessible through said aperture for temporary attachment of means for holding a lading in place, said rod being positioned within said box struc-

ture to provide an opening on each side thereof, a deck beam having spaced apart prongs adapted to enter said openings and be supported by said box structure, and means to retain said 5 prongs within said openings.

2. In a railway car having a wall comprising a sheathing and a lining, in combination with an anchorage device supported by said wall and comprising a solid box-like structure entirely 10 closed except for an opening therein accessible from the interior of the car through an aperture in said lining, whereby foreign matter passing through said aperture cannot get between said sheathing and said lining, a member secured to 15 said device so as to be accessible from the interior of the car for anchoring a lading thereto by a steel tape or the like, said device being arranged to support one end of a deck beam, said device being provided with means to cooperate with said 20 deck beam to prevent the horizontal disengagement of said deck beam from said anchorage device.

3. In a railway car having a wall comprising posts, a sheathing and a lining in combination 25 with an anchorage device supported by said posts and positioned between the sheathing and the lining, said device comprising spaced apart horizontally disposed members extending between and secured to said posts, a U shaped piece 30 extending between and secured to said members to form a five sided solid box structure with the sixth side thereof open to the interior of the car through an aperture in said lining and a vertical bar accessible from the inside of the car through 35 said aperture for anchoring a lading strap thereto, said bar being secured to said members and positioned between the arms of the U shaped piece so as to provide an opening on each side thereof, a deck beam having spaced apart prongs 40 adapted to enter said openings and be supported by said box structure, and means to retain said prongs within said openings.

4. In a railway car having a wall comprising a sheathing and a lining, in combination with an 45 anchorage device supported by said wall and comprising a solid box-like structure entirely closed except for an opening therein accessible from the interior of the car through an aperture in said lining, whereby foreign matter passing through said aperture cannot get between said sheathing and said lining, a member secured to 50 said device so as to be accessible from the interior of the car for anchoring a lading thereto by a steel tape or the like, said device being arranged to support one end of a deck beam, and means mounted partially on said device and partially on said deck beam, whereby said beam can 55 only be disengaged from said device by upward and horizontal movements of the beam.

KARL F. NYSTROM.
